UNITED STATES PATENT OFFICE

118,738

DESIGN FOR A COMBINED PORCH LAMP AND SIGN

Jesse B. Herring, Birmingham, Ala.

Application July 5, 1939, Serial No. 85,850

Term of patent 7 years

To all whom it may concern:

Be it known that I, Jesse B. Herring, a citizen of the United States of America, residing at Birmingham, in the county of Jefferson and State of Alabama, have invented a new, original, and ornamental Design for a Combined Porch Lamp and Sign, of which the following is a specification, reference being had to the accompanying drawing, forming part thereof.

Fig. 1 is a plan view of a combined porch lamp and sign, showing my new design;

Fig. 2 is a front elevational view; and

Fig. 3 is a side elevational view.

I claim:

The ornamental design for a combined porch lamp and sign, as shown.

JESSE B. HERRING.
